Primary Examiner — Robert M Spear*Assistant Examiner* — Kendra L Hamilton(74) *Attorney, Agent, or Firm* — Taylor English Duma LLP(57) **CLAIM**

We claim the ornamental design for a pet leash, as shown and described.

DESCRIPTION

FIG. 1 is a perspective view of the claimed design.

FIG. 2 is a front view thereof.

FIG. 3 is a back view thereof.

FIG. 4 is a right-side view thereof.

FIG. 5 is a left-side view thereof.

FIG. 6 is a top view thereof.

FIG. 7 is a bottom view thereof; and,

FIG. 8 is a perspective view of the claimed design showing the leash being used with a dog.

In the drawings, the broken lines showing of a user, a dog and a toy depict environmental subject matter only and form no part of the claimed design. The broken lines on the leash represent stitching that forms part of the claimed design.
